Samuel Randall
Letters Patent

1472X

The apparatus referred to in the Letters Patent and making
part of the same containing a description and the name of the
said Samuel Randall himself of this, depicting an wrought

A main flue or pipe through which the air must pass before
it can ascend in the chimney pipe or pipe placed under the coal
or a vessel of the fire in the back or side of whatever contains
the coal &c. and adjacent to the bottom of it so that no air
can pass off in the chimney pipe or pipe without first passing
through and entering by an opening into and through the coal or vessel
of the fire that is the fire itself.

The face of this draught may be governed by a movable
plate of cast or sheet iron placed above the fire or in a chimney
that will readily or partially supply the chimney pipe or
pipe with unheated air. This principle of the draught may
be applied to any fire place stove or furnace.
